Inventor:
J. P. Kwasigroch.
by Hazard & Miller Atty.

UNITED STATES PATENT OFFICE.

JOSEPH P. KWASIGROCH, OF LOS ANGELES, CALIFORNIA.

REENFORCED LATHING.

Application filed January 12, 1922. Serial No. 528,723.

To all whom it may concern:

Be it known that I, JOSEPH P. KWASIGROCH, a citizen of the United States, residing at Los Angeles, in the county of Los Angeles and State of California, have invented new and useful Improvements in Reinforced Lathings, of which the following is a specification.

My invention relates to lathing used in wall structures, and a purpose of my invention is the provision of a reenforced lathing of extremely simple, durable and efficient construction and which operates to effectively sustain plaster thereon in the building of walls thereby minimizing the possibility of the plaster dropping from the walls.

I will describe one form of lathing embodying my invention and will then point out the novel features thereof in claims.

In the accompanying drawings,

Figure 1 is a fragmentary view showing in side elevation with a portion thereof broken away, one form of lathing embodying my invention in applied position with respect to a wall studding.

Fig. 2 is a horizontal sectional view taken on the line 2—2 of Fig. 1.

Fig. 3 is a view similar to Fig. 2 showing the plaster in applied position with respect to the lathing.

Referring specifically to the drawings in which similar reference characters refer to similar parts, my invention, in its present embodiment, comprises laminated sheets 15 and 16 preferably formed of paper and suitably secured to each other as by adhesive material, and between which are interposed a foraminous material 17, such as wire netting or the like. The sheets 15 and 16 are formed at regular intervals with orifices 18 so arranged as not to be intercepted by the strands comprising the wire netting in the manner clearly shown in Fig. 1.

45 In the applied position of the lathing as

shown in Figs. 1 and 2, it is adapted to be secured to the wire studding 19 by means of nails 20 or other suitable fastening means which are driven through the sheets and into the studs in the manner clearly shown. 50

With the plaster in applied position upon the lathing as shown in Fig. 3, portions thereof project through the orifices 18 so that when it is set, these portions serve to securely lock the plaster upon the lathing 55 and thus prevent falling of the plaster, as will be understood.

Although I have herein shown and described only one form of lathing embodying my invention, it is to be understood that 60 various changes and modifications may be made herein without departing from the spirit of the invention and the spirit and scope of the appended claims.

I claim as my invention:

1. A lathing comprising laminated sheets secured to each other and having registering orifices therein, and a metallic foraminous material between the sheets and so arranged as to have the mesh thereof in registration with said orifices. 70

2. A lathing comprising laminated sheets of flexible material having registering orifices, and depressed portions cooperating with each other to provide pockets, and a 75 wire screen interposed between the sheets and having the intertwined portions disposed within said pockets and having the meshes thereof in registration with said orifices.

3. A lathing comprising laminated sheets of flexible material having registering orifices, and depressed portions co-operating with each other to provide pockets, and a wire screen interposed between the sheets 85 and having the intertwined portions disposed within said pockets.

In testimony whereof I have signed my name to this specification.

JOSEPH P. KWASIGROCH.
